CLAIM

The ornamental design for a massage appliance, as shown
and described.

DESCRIPTION

FIG. 1.1 is a bottom, front, left side perspective view of a
massage appliance showing my new design;
FIG. 1.2 is a top, rear, left side perspective view thereof;
FIG. 1.3 is a front elevation view thereof;
FIG. 1.4 is a rear elevation view thereof;
FIG. 1.5 is left side elevation view thereof;
FIG. 1.6 is right side elevation view thereof;
FIG. 1.7 is a top plan view thereof; and
FIG. 1.8 is a bottom plan view thereof.

(Continued)

The broken lines depict portions of the massage appliance that form no part of the claim.
